(57) **CLAIM**

The ornamental design for a needle-based device with a safety mechanism, as shown and described.

DESCRIPTION

FIG. 1 is an exploded front top-right side perspective view for a needle-based device with a safety mechanism, showing my new design in a disassembled configuration;

FIG. 2 is a front elevational view of FIG. 1 thereof;

FIG. 3 is a rear elevational view of FIG. 1 thereof;

FIG. 4 is a left side elevational view of FIG. 1 thereof;

FIG. 5 is a right side elevational view of FIG. 1 thereof;

FIG. 6 is a front top-right side perspective view of a needle-based device with a safety mechanism of FIG. 1 thereof, in an assembled configuration;

FIG. 7 is a front elevational view of FIG. 6 thereof;

FIG. 8 is a rear elevational view of FIG. 6 thereof;

FIG. 9 is a left side elevational view of FIG. 6 thereof, the right side elevational view being a mirror image;

FIG. 10 is a top plan view of FIG. 6 thereof;

FIG. 11 is a bottom plan view of FIG. 6 thereof;

FIG. 12 is a front top-right side perspective view of a needle-based device with a safety mechanism of FIG. 6 without the outer cover thereof;

FIG. 13 is a left side elevational view of FIG. 12 thereof, the right side elevational view being a minor image; and,

FIG. 14 is a top plan view of FIG. 12 thereof.

The needle-based device with a safety mechanism is shown with a symbolic break in length. Any portions not shown between the break lines form no part of the claimed design. The broken lines indicate portions of the needle-based device with a safety mechanism that form no part of the claimed design.
